DRAFT ROLLER TREATING MACHINE

Saint Julian Geddings, West Columbia, S. C.

Application November 21, 1946, Serial No. 711,352

3 Claims. (Cl. 153—48)

1

My invention relates to apparatus for separating, assembling, and straightening draft roller sections employed upon spinning frames.

In a spinning frame, a roller beam is provided, upon which bearings are rigidly mounted, and these bearings support the lower draft rollers, usually three in number. These draft rollers are long and extend for the entire length of the spinning frame. The draft rollers are made in sections, which must be separated, so that section or sections may be removed for repair or replacement. There are short upper draft rollers arranged directly above the lower draft rollers. The upper short draft rollers are supported in saddles, which are mounted upon the draft beam and weights are connected with these saddles by rods or chains passing through openings in the roller beam. These weights move the upper draft rollers toward the lower draft rollers. The saddles and the upper draft rollers may be readily removed from proximity to the lower draft rollers and laid back on the spinning frame, thus leaving the lower draft rollers uncovered. These lower draft rollers remain in their bearings and are now accessible so that either of them can be lifted out of their bearings.

The present invention has to do with means to separate the lower draft roller sections, to assemble the lower draft roller sections, and to straighten the assembled lower draft roller sections.

In order to properly perform these various operations, I provide a plurality of brackets which I mount upon the roller beam. These brackets have sockets or forks for receiving either lower draft roller when it is removed from its bearings, and will support the lower draft roller above the draft beam, and forwardly of the same.

I provide an upstanding stand or frame, mounted upon wheels, so that it may be rolled into proper relation to and from the lower draft roller held within the brackets. A vertically adjustable carriage or tray is mounted upon the stand, and this carriage or tray has a hydraulic press mounted thereon. Means are provided to raise and lower the carriage or tray and hold the same at the selected elevation.

I provide a separating unit to be applied to and operated by the hydraulic press; an assembling unit to be applied to the hydraulic press and operated thereby; and a straightening unit to be applied to the press and operated thereby.

The separating unit, assembling unit, or straightening unit may be applied to the press and the upstanding frame or stand rolled toward

2

the brackets, to bring the unit beneath the bracket-supported draft roller, subsequently to which the carriage or tray is raised, to bring the unit at the proper elevation for acting upon the draft roll sections.

In the accompanying drawings forming a part of this application and in which like numerals are employed to designate like parts throughout the same,

10 Figure 1 is a side elevation of the stand and hydraulic press equipped with the straightening unit,

Figure 2 is a front elevation of the stand and associated elements, parts in section,

15 Figure 3 is a rear elevation of the same, parts broken away,

Figure 4a is a plan view of the operating lever,

Figure 4 is a plan view of the straightening unit,

20 Figure 5 is a longitudinal section taken on line 5—5 of Figure 4,

Figure 6 is a transverse vertical section taken on line 6—6 of Figure 4,

Figure 7 is a plan view of a separating unit,

Figure 8 is a transverse vertical section taken on line 8—8 of Figure 9,

Figure 9 is a horizontal section taken on line 9—9 of Figure 8,

Figure 10 is an end elevation of the separating unit, parts omitted,

30 Figure 11 is a plan view of the assembling unit, parts broken away,

Figure 12 is a front side elevation of the assembling unit,

Figure 13 is a vertical longitudinal section taken on line 13—13 of Figure 11,

Figure 14 is a transverse vertical section taken on line 14—14 of Figure 11,

Figure 15 is a plan view of the draft roller brackets, and the associated spreading unit,

40 Figure 16 is a side elevation of the draft roller supporting bracket,

Figure 17 is a plan view of the same,

Figure 18 is an end elevation of a portion of the straightening unit showing the same rolled beneath the journal of the assembled draft roller sections,

Figure 19 is a similar view, showing the same raised so that the journals are centered and engaged within the jaws of the straightening unit,

45 Figure 20 is an end elevation of a portion of the separating unit, showing the same moved beneath the journals of the assembled draft roller sections,

Figure 21 is a similar view, showing the separating unit raised so that the journals are received within the openings of the jaws of the separating unit.

Figure 22 is an end elevation of a portion of the assembling unit showing the same moved beneath the journals of the roller sections.

Figure 23 shows the unit raised so that the journals are received within the lower portions of the clamps of the assembling units.

Figure 24 is a plan view of the bending unit.

Figure 25 is an end elevation of same, parts omitted, and

Figure 26 is a side elevation of same, parts omitted.

In Figures 1 to 3 inclusive, I have shown an upstanding stand or frame, comprising upstanding legs 25, arranged in a rectangular group, and converging upwardly. These legs are rigidly connected near their lower ends by horizontal tubes 26, upon which is rigidly mounted a box 21, for holding tools, parts, or the like. The legs 25 are preferably tubular and the lower ends of these tubular legs are internally screw threaded for receiving screw threaded shanks 28 rigidly secured to yokes 29 of caster wheels 30. By turning the screw threaded shanks 28 within the lower ends of the legs 25, these legs may be vertically adjusted, and the shanks 28 are locked in the selected adjusted position by set screws 31. Rigidly secured to the upper ends of the legs 25 are couplings 32 which are rigidly secured to a horizontal frame 33, including sides 34 and 35 and U-shaped ends 36 and 37. Rigidly secured to the end 36 is a vertical strap 38, the lower end of which is rigidly secured to a horizontal strap 39, in turn rigidly secured to the adjacent legs 25. Guide sleeves 41 and 42, are rigidly secured to the vertical strap 38, and slidably receive a vertical reciprocating rod 43. The rod 43 extends through the open frame 33 and is rigidly secured to a carriage or tray 44. This carriage or tray is horizontal and is circularly curved in vertical cross section, to provide an upper curved recess, to receive the cylinder of a hydraulic press, to be described.

Rigidly secured to the horizontal strap 39 are vertical ears or knuckles 45, receiving between them the head 46 of a forked lever 47. This head is pivotally connected with the knuckles 45 by a pin 47'. The forked end of the lever is pivoted to the vertical rod 43 by means of a pin 48, operating within elongated slots 49 formed in the forked end of the lever 47. Pivotally connected with the lever 47, as shown at 50, is a weighted dog 51, for coaction with a stationary generally vertical quadrant 52, the upper end of which is rigidly secured to the U-shaped end 37, as shown at 53. This quadrant has a lower notch 54, an intermediate notch 55, and an upper notch 56, as shown. The dog 51 is adapted to engage in these notches.

The numeral 57 designates a hydraulic press substantially identical with the hydraulic press shown in my pending application for Hydraulic draft roll press, filed January 3, 1946, Serial number 638,862. This press includes a horizontal cylinder 58 and a plunger 59, having an opening 60 formed therein and a set screw 61, leading to the opening. The hydraulic press may be manually operated by a handle 60'. The cylinder 58 is provided at its top with a handle 61'. The cylinder 58 is provided upon its sides with lugs or trunnions 62, for insertion within notches 63 formed in vertical ears 64, formed integral with

the carriage or tray 44. When the ears 64 engage the frame 33 they limit the downward movement of the carriage or tray 44. The cylinder 58 is mounted upon and within the carriage or tray 44, and the trunnions 62 are held within the opening 63, thus preventing the cylinder 58 from moving longitudinally with respect to the carriage or tray.

Several units are applied to and operated by the hydraulic press. The first unit to be described is the straightened unit. This unit, Figures 1, 2, 4, 5, and 6 comprises a horizontal bar 62', having rigid links 63' arranged beneath it and rigidly secured thereto. These links have upwardly offset ends terminating in horizontal extensions 64'. The bar 62' has a recess 65, Figure 6, which is curved in cross section, receiving a cylindrical guide rail 66, rigidly attached to the bar 62 by rivets 66', or the like. The guide rail 66 has its vertical diameter disposed outwardly of the bar 62'. Slidably mounted upon the guide rail 66 are jaws 67, having vertical V-shaped recesses 68. Adjustably mounted upon the top of the bar 62' is a slide 69, having elongated slots 70, for receiving set screws 71, having screw threaded engagement with the bar 62'. The slide may be longitudinally adjusted upon the bar 62' and locked in the selected adjusted position. The slide 69 has a vertical head 72, provided with a transverse groove 73, and a set screw 74 engages the head 72, upon one side of the groove 73. The set screw has a clamping portion 75, projecting over the groove 73, and a washer 76 is preferably arranged beneath the clamping portion 75 and also projects over the groove 73. The groove 73 is adapted to receive a slide 77 which is adjustable therein and clamped in position by the set screw 74. This slide carries a vertical post 77', having a horizontal extension 78, held in an opening 79' of the slide 77, and having a friction fit therein, so that the post 77' can be adjusted to the vertical position. A guage 79 is provided, having a finger 80, to engage with the assembled draft roller sections or their journals, for determining if the assembled sections are straight. This guage is mounted upon an arm 81, having a vertical opening 82, to receive the post 77' and the post is clamped in the opening 82 by a set screw 83.

The cylinder 58 is provided with horizontal apertured lugs or knuckles 84, for insertion within the forked ends of rigid links 85, and connected therewith by pins 86, passing through these apertured elements. The opposite ends of the links 85 are forked and these forked ends are apertured to receive the apertured extensions 64' and these apertured elements are connected by pins 87. The links 85 may ordinarily remain attached to the lugs 84, while the links 63' are separated from the links 85, when it is desired to remove the straightening unit. The numeral 88 designates a bending tool, having a shank 89 for insertion within the opening 60, and clamped therein by the set screw 61.

In Figures 7 to 10 inclusive, I have shown a separating unit, which is substantially identical with the separation unit shown in my said application 638,862. This separating unit comprises a relatively stationary guide 90, which is straight and elongated and formed generally U-shaped in cross section. This guide includes a bottom 91 and sides 92, having inwardly extending horizontal flanges 93. The ends of the guide 90 are open. Disposed within the guide 90 are slides or

carriages 94, which move in a straight line. At their inner ends, these slides or carriages carry vertical ears or jaws 95, integral therewith. These jaws have vertical jaws or slots 96, for the reception of the journals, to be described. The jaws 95 are at right angles to the longitudinal axis of the slides or carriages 94. At their inner ends, the slides or carriages 94 are provided at their bottoms with recesses or notches 97, forming horizontally inclined faces 98, Figure 9, which converge transversely of the guide 90. One side 92 has an opening 99, and the other side 92 has an opening 100. Adapted to be arranged between the inclined faces 98 is a tapered expanding element or head 101, to enter the openings 99 and 100. This expanding element or head has a shank 102. This shank is adapted for insertion within the opening 69 of the plunger 59 and to be clamped therein by the set screw 61. One side 90 is provided near its ends with apertured knuckles 103, for insertion within the forked ends of the links 85, and to be held therein by the pins 87. Rigidly secured to the knuckles 103 are stops 104, having inturned ends 105, to limit the rearward movement of the tapered or expanding element 101.

I have shown an assembling unit in Figures 11 to 14 inclusive, which is substantially identical with the assembling unit shown in my said application 638,862. This assembling unit comprises a horizontal housing or guide 106, including a bottom 107, a top 108, and sides 109, Figure 14. One side 109 has openings 110 and the opposite side 109 has openings 111. The ends of the housing or guide are open, as shown. Mounted to reciprocate within the guide 106 are slides or carriages 112, provided at their ends with clamps 113, integral therewith. Each clamp comprises a lower part 114 and an upper part 115, having semi-cylindrical recesses 116, which when assembled form a cylindrical recess for receiving the journals, to be described. The upper part 115 has wings 117 and the lower part wings 118 and these wings are connected by bolts 119. The numeral 120 designates a forked contracting element or head, including spaced portions or tines 121, having straight outer edges 122 at right angles to the carriages 112, and inner inclined edges 123 which engage inclined walls 124 of recesses 125 formed in the bottoms of the carriages 112. The free ends of the tines 121 are connected by a bar 124. The contracting element or head 120 is provided with a shank 126, for insertion within the opening 69, and to be clamped therein by the set screw 61. The housing or guide 106 is provided at its ends with horizontal rigid arms 127, having apertured knuckles 128 to be inserted within the outer forked ends of the links 58 and held therein by the pins 87.

Attention is now called to Figures 15, 16 and 17. The numeral 129 designates the roller beam of a spinning frame. The bearings for the lower draft rollers, and the saddles for the upper draft rollers, and associated elements are omitted. The numeral 130 designates brackets, which are rigidly mounted upon the roller beam 129, preferably at the meeting ends of the draft roller sections, but may be arranged at other points. Each bracket 130 includes an upstanding shank 131, provided at its top with a generally U-shaped socket or head 132, having a copper rib 133 mounted upon the upper face of the fork 132. The purpose of this copper rib is to provide a soft supporting element for the journals, which will not scratch them. The shank 131 is rigidly secured to a generally horizontal base 134, the

free end of which is provided with longitudinal slots 135, receiving bolts 136, secured to the roller beam 129. These bolts may be passed through the openings through which the chains or rods pass, which are connected with the saddles of the upper draft rollers and which carry the usual weights. Rigidly connected with each base 134 is an L-shaped gauge or stop 137, to contact with the front face of the roller beam 129, thus insuring that the several brackets 130 will be in alignment.

In Figure 15, the numeral 138 designates one of the lower draft rollers of the spinning frame which extends for the entire length of the roller beam 10. This draft roller is shown as removed from its bearings carried by the draft beam 129 and supported within the sockets 132 of the brackets. This draft roller 138 is formed in sections 139 and 140, which are ordinarily 22 inches long. The intermediate sections 139, Figure 12, are provided at corresponding ends with cylindrical journals 141, carrying extensions 142, which are square in cross section, for insertion within the openings or sockets 143, formed in the corresponding ends of companion sections 139 and the inner ends of the sections 140. These openings or sockets are also square in cross section and the extensions 142 have a driving fit within the sockets 143. At their outer ends, the sections 140 have the journals 141, but the extensions 142 are omitted. The several journals 141 are held within the bearings of the spinning frame, which are mounted upon the roller beam 129. Each roller section 139 and 140, has fluted roller members 144, which are spaced, and smooth cylindrical portions 145 arranged between the fluted roller members. At their ends, the roller sections 139 and 140 have smooth cylindrical portions 146, of larger diameter than the journals 141, forming shoulders 147. The journals 141 are held within the draft roller bearings which are mounted upon the roller beam 129.

The operation of the machine is as follows:

When the lower draft roller sections are to be separated and removed, the saddles carrying the upper draft rollers are removed and laid back on the spinning frame. The lower draft rollers 138 now remain within their bearings, and are uncovered and are now accessible so that either of them can be removed. The brackets 130 are now rigidly mounted upon the roller beam 129. The selected draft roller 138 is removed from its bearings and supported in the sockets 132 of the brackets 130, at an elevation above the roller beam 129 and forwardly of the same.

The first operation is to separate the selected draft roller sections, and for the purpose of illustration, I have shown the separation of the draft roller sections 139, Figure 15. The separating unit is now applied to the hydraulic press 57 and the lever 47 is swung to the lowermost position so that the dog 51 is beneath the notch 54 and the lugs 64 engage the frame 33. The stand or carriage carrying the hydraulic press is now rolled in proximity to the draft roll 138 supported in the brackets. The jaws 95 should pass beneath the journal 141 of the draft roller sections 139, with a clearance of about one-eighth to one-quarter of an inch. If this clearance is not provided, the frame or stand is vertically adjusted by turning the shanks 28 within the legs 25, until such clearance is provided, and the shanks are locked in the adjusted position by the set screws 31. This adjustment will provide suitable clearance for the other units when applied to the hydraulic press. The stand or frame is then rolled

toward the draft roller 138, until the jaws 95 pass beneath the journal 141 and the openings 96 are in alignment with this journal, Figure 20. The lever 47 is now moved upwardly so that the dog will enter the second notch 55 from the bottom, and this will raise the jaws 95 so that their openings 96 will receive the journal 141. The hydraulic press 57 is now operated so that its plunger 86 moves outwardly and the expanding element 101 will move forwardly, separating the carriages 94. The jaws 95 engage the shoulders 147, and the extension 142 is withdrawn from the socket 143. The lever 147 is now returned to the lowermost position and the carriage or stand rolled from the draft roller 138. The same operation is repeated for separating the opposite end of the draft roller section 139 from its companion draft roller section 140.

After the journals of the removed draft roller section are repaired, or a new draft roller section substituted for the removed draft roller section, the assembling unit is mounted upon the hydraulic press. The lever 47 is in the lowermost position. The stand or carriage is now rolled toward the draft roller 138 and the lower parts 114 of the clamps are arranged beneath the smooth portions 145 and the recesses 116 are in alignment with the portions 145, Figure 22. The lever 47 is now swung upwardly so that the dog 51 enters the first notch 54 from the bottom, and this raises the clamp parts 114 so that the recesses 116 receive the portions 145, Figure 23. The upper clamp parts 115 are now secured to the lower clamped parts. The hydraulic press is now operated and the element 120 is moved forwardly which moves the carriages 112 inwardly. This action introduces the extension 142 into the socket 143, Figure 12. The top clamp parts 115 are then removed, and the lever 47 is swung to the lowermost position, whereby the lower clamp parts 114 assume the position shown in Figure 22. The stand or frame is now rolled from the draft roll 39.

The straightening unit is now applied to the hydraulic press, and the lever 47 is in the lowermost position, and the stand or carriage rolled toward the draft roller 138. The straightening unit passes beneath the round portions 145, Figure 18. The lever 47 is now swung up so that the dog 51 engages in the uppermost notch 56. This will bring the jaws 67 to the raised position, Figure 19, so that the notches 68 of the jaws are centered with respect to the round portions 145 and 146. The stand or carriage may be rolled slightly from the rod so that the portions 145 and 146 will enter the notches 68. The hydraulic press is now operated and the straightening tool 88 will engage the journal 141, bending and straightening the assembled draft roller sections. The guage is now applied to the slide 63 and its finger 86 will engage the journal 146 or other part of the draft roller, thus indicating when the same has been straightened. The draft roller may be released from clamped action, while held within the jaws 67, so that it may be turned and the straightening tool 88 again forced against the draft roller. After the straightening operation has been completed, the lever 47 is again returned to the lowermost position so that the jaws 67 will be lowered with respect to the round portions 145. The stand or carriage is now rolled from the draft roller. A similar operation is repeated for inserting the extension 142 of the next draft roll section into the socket in the companion draft roll section.

The draft roller of a spinning frame is a precision made part and must be maintained in accurate adjustment for the spinning frame to properly operate and produce the best results.

5 My machine is therefore a precision machine, which will separate and assemble the draft roller sections, without injury or bending the same, and if the draft roller sections have become bent prior to their separation or assembling, the machine 10 will restore them to the precise straight condition. My machine is brought to the spinning frame and the draft roller to be treated is removed from the bearings of the spinning frame and mounted upon the brackets secured to the frame beam. This 15 provides the minimum transporting of the draft roller, for treatment and replacement.

The invention is in no way restricted to the general description of the same in the introductory portion of the application or to the detailed 20 description, but resides in the various combinations and sub-combinations as defined by the claims.

It is to be understood that the forms of my 25 invention herewith shown and described are to be taken as preferred examples of the same, and that various changes in the shape, size, and arrangement of parts may be resorted to without departing from the spirit of my invention or the scope of the subjoined claims.

30 Having thus described my invention, what I claim is:

1. Apparatus for use in connection with a sectional draft roller supported generally horizontal at a selected elevation, said apparatus comprising 35 a portable stand, wheels vertically adjustably mounted upon the lower end of the stand, a vertically movable carriage mounted upon the upper portion of the stand, means to raise and lower the carriage with respect to the same, lugs carried by the carriage and having generally vertical notches, a press removably mounted upon the carriage and including a cylinder and plunger, said cylinder having trunnions for insertion within the notches, a device for holding engagement 45 with the draft roller, means to mount the device upon the cylinder, and a reciprocatory element mounted upon the plunger and associated with the holding device for applying force to the sectional draft roller while held by the holding device, the arrangement being such that the device, reciprocatory member and cylinder are removable as a unit from the carriage.

2. Apparatus for use in connection with a sectional draft roller supported generally horizontal at a selected elevation, said apparatus comprising 55 a portable stand, a vertically movable carriage mounted upon the stand near its upper end and provided upon its upper face with a recess and having parts provided with notches, means connected with the stand and carriage to move the carriage vertically with relation to the stand and hold the same at the selected position, a press mounted upon the carriage and including a cylinder and plunger, trunnions carried by the 60 cylinder, the cylinder being removably mounted within the recess and the trunnions passing into the notches, a bar disposed in opposed relation to the end of the plunger and spaced from the cylinder, links secured to the bar and to the cylinder, spaced jaws mounted upon the bar and facing toward the plunger, and a bending element mounted upon the plunger and arranged to engage with the sectional draft roller at a point between the jaws.

75 3. Apparatus for use in connection with a sec-

tional draft roller supported generally horizontal at a selected elevation, said apparatus comprising a portable stand, a vertically movable carriage mounted upon the stand near its upper end and provided upon its upper face with a recess, lugs secured to the carriage adjacent to its opposite sides and projecting above the sides and having notches, means connected with the stand and carriage to move the carriage vertically with relation to the stand and hold the same at the selected position, a press mounted upon the carriage and including a cylinder and plunger, trunnions secured to the sides of the cylinder, the cylinder being removably mounted within the recess and the trunnions passing into the notches, lugs rigidly secured to the cylinder near its end and projecting laterally beyond the cylinder and arranged above the carriage, the lugs being adapted for attachment to the draft roller en-

gaging member and the plunger being adapted for attachment to a force applying element.
